UNITED STATES PATENT OFFICE.

GUSTAV W. PETERSON, OF BRADFORD, PENNSYLVANIA.

SAFETY BAND.

Application filed April 22, 1924. Serial No. 708,200.

To all whom it may concern:

Be it known that I, GUSTAV W. PETERSON, a subject of the King of Sweden, residing at Bradford, in the county of McKean and 5 State of Pennsylvania, have invented certain new and useful Improvements in a Safety Band, of which the following is a specification.

This invention relates to improvements in 10 safety bands adapted to be used on various articles.

An important object of this invention is to provide a band adapted to be placed upon a pencil or the like and prevent the same 15 from dropping from the pocket of the wearer.

A further object of the invention is to provide a device of this character which may be utilized on watches and like articles to 20 prevent the same from dropping from the pocket when the person is leaning or when it is apt to be jarred therefrom.

A still further object of the invention is to provide a device of this character which 25 is simple, yet durable of construction and efficient for the purpose intended.

Other objects and advantages of this invention will be apparent during the course 30 of the following description.

In the accompanying drawing forming a part of this specification and in which like numerals are employed to designate like parts throughout the same:

Figure 1 is an enlarged perspective view 35 of the device embodying my invention.

Figure 2 is a modified form of my invention mounted upon a pencil,

Figure 3 is a side elevation of the device mounted upon a watch, and

Figure 4 is a vertical sectional view taken through the center thereof.

In the drawing, wherein for the purpose of illustration is shown the preferred embodiment of my invention, the numeral 5 generally denotes a band preferably constructed of rubber or other resilient material and substantially circular in cross section. The lower portion of the band 5 comprises a cylindrical retaining collar 6 which should be smaller in diameter than the pencil or article upon which it is to be used in order

to snugly fit the same and prevent removal therefrom.

The upper extremity of the band has a plurality of prongs or projections 7 extending upwardly and outwardly formed thereon, adapted to engage the pocket of the garment. 55

In Figure 2 I have illustrated a modified form of the device mounted upon a pencil, 60 the retaining collar 6 having a rubber extension 8 formed or secured thereon and adapted to be used as an eraser.

In Figure 3 I have shown the device mounted upon a watch, the retaining collar 65 6 in this case being somewhat smaller in diameter than the watch stem and adapted to adhere tightly thereto, the device being further prevented from displacement by the bow 9 usually employed in the construction 70 of watches.

In use, it is obvious that this device may be employed on numerous articles carried about the person the device being constructed in different sizes in order to be used on various shaped articles. It is particularly adapted for use upon pencils which are easily displaced from the pocket of the wearer upon leaning over or jarring the person often resulting in broken leads or other inconveniences. It is obvious that this device will prevent dropping of such articles from 75 the pocket as the extending projections will engage the sides of the pocket and prevent the pencil or other article from being 80 dropped to the floor.

It is to be understood that the form of my invention herewith shown and described is to be taken as the preferred example of the same, and that various changes as to the 90 shape and size thereof may be resorted to without departing from the spirit of the invention or the scope of the subjoined claims.

Having thus described my invention, I claim:

1. A device of the character described comprising, a cylindrical retaining collar, a plurality of pointed projections or prongs formed on the upper edge of the said collar, and an extension formed on the side of 100 the collar adapted to act as an eraser.
2. A safety band comprising a body of

2
elastic material open from end to end and having side walls of uniform transversal thickness from end to end, one end portion of the body being cylindrical and the other end portion of the body being bell mouthed, the bell mouthed shaped portion of the body being scalloped at its edge to form prongs leading in from the edge of the bell mouthed portion and terminating at their inner ends short of the cylindrical portion of the body. ¹⁰ In testimony whereof, I have affixed my signature.

GUSTAV W. PETERSON.
